UNITED STATES PATENT OFFICE.

THOMAS PAUL FORMAN, OF WATERBURY, CONNECTICUT.

NECKTIE-CASE.

1,061,906.

Specification of Letters Patent.

Patented May 13, 1913.

Application filed April 5, 1912. Serial No. 688,647.

To all whom it may concern:

Be it known that I, THOMAS P. FORMAN, a citizen of the United States, and a resident of Waterbury, in the county of New Haven 5 and State of Connecticut, have invented a new and Improved Necktie-Case, of which the following is a full, clear, and exact description.

This invention relates to improvements in 10 necktie cases, and has for an object to provide an improved structure which is adapted to be folded so that the respective ties will face each other and all the ties be covered when the case is closed.

15 Another object of the invention is to provide an improved case formed with folders or retaining members having spring-pressed portions designed to press against the ends of folded neckties for holding the same 20 properly in the case.

In carrying out the objects of the invention, a case is provided formed from any desired kind of material, and arranged to lie flat when in an unfolded condition. Arranged at spaced intervals at each side of 25 the case are spring-pressed clamping members designed to clamp ties to the back or body portion of the case. These clamping members are so arranged that the ties may 30 be caused to be arranged in sets or pairs when the case is folded or closed.

A practical embodiment of the invention is represented in the accompanying drawings forming a part of this specification, in 35 which similar characters of reference indicate corresponding parts in all the views.

Figure 1 is a perspective view of an embodiment of the invention, the same being shown partly closed; Fig. 2 is a longitudinal 40 vertical section through an embodiment of the invention while in the closed position; Fig. 3 is an end view of an embodiment of the invention, the same being shown partially open and the respective parts spaced 45 slightly apart for the purpose of illustration; Fig. 4 is a longitudinal vertical section through one of the tie supporting braces and clamping extension associated therewith; Fig. 5 is a perspective view of a 50 slightly modified form of the invention, the same being shown open; Fig. 6 is a fragmentary view through Fig. 5, partially on the line 6-6; Fig. 7 is a view similar to Fig. 6 except that the same shows the device in 55 an open position; and Fig. 8 is an end view of the structure shown in Fig. 4.

Referring to the accompanying drawings by numerals, 1 indicates the body portion of a case which may be formed of cloth, leather, or other material, as desired. The 60 body portion 1 is formed with side members 2 and 3, and a flap 4. The body portion 1 is preferably made from a double layer of material, though this is not absolutely necessary. Connected to the body portion 1 are 65 a plurality of stiff supporting or bracing members 5 which may be covered with any desired material. The members 5 are preferably made from metal and have their ends turned up forming ears 6 and 7 (Fig. 8), for 70 receiving a pintle 8. A clasping extension 9 is also provided formed with a projecting portion 10 having depending ears 11 and 12 through which the pintle 8 extends. This pintle connects the bracing members 5 and 75 the clamping extension 9 together. In order to cause the clamping extension or plate 9 to press against the bracing members 5, or have a tendency to press against the bracing members 5, a spring 13 is wound around the 80 pintle 8 and formed so that its ends will project through or be secured to the extension 9 and bracing member 5, as clearly shown in Fig. 4. A clamping member 9 is formed at each end of the bracing members 85 5 so as to engage the respective ends of the necktie 14.

The bracing members 5 on the back 1, are arranged so as to form sections 15, 16, 17 and 18. In folding the case the sections 90 17 and 18 are folded together face to face so that the neckties arranged therein will be in contact and the neckties in section 15 will be facing upward, as shown in Fig. 1. After the case has been folded to the position 95 shown in Fig. 1, a pivotal movement of all of the sections 15, 16, 17, toward the section 18 will cause the correct folding of the case. After this has been done the end 3 is moved to its correct position and the flap 4 is folded 100 over so that the clasping stud 19 may be used for securing the case in a closed position, a suitable socket being provided for accommodating the stud 19.

In Figs. 5 to 7 inclusive will be seen a 105 slightly modified form of the invention in which the body 1 is provided with a plurality of turned over flaps or ends 20 at each edge of the body portion. These flaps or turned over ends 20 are held in place by lines 110 of stitching 21 and by an elastic 22 which permits the respective turned over portions

20 to be raised for the insertion of the ends of the neckties. In this form of the invention it will be observed that the clasping member formed by the turned over ends 20
5 cannot be raised pivotally as in the preferred structure, as the line of stitching 21 will hold part of the same down. However, the corners to which the elastic 22 are secured may be raised sufficiently for the insertion of
10 the ends of the desired number of neckties. This form of the invention is designed to be folded in a similar manner to the preferred form, namely, the sections 16 and 17 are designed to be folded together which will
15 cause the face of section 18 to be uppermost. After this is done the case is folded again so that the upper face of section 15 will be in contact with the face of section 18.

Connected to the side portion 3 is a pad
20 or strip of cloth or other material 23, held in place by lines of stitching or otherwise if desired. This pad or strip of cloth 23 is designed to receive one or more stick pins
24 or other similar articles. It will be noted
25 that as the stick pin 24 is arranged on the side the same will not in any way come in contact with the neckties so as to injure or displace the same.

Having thus described my invention I claim as new and desire to secure by Letters Patent:—

In a necktie case or holder a body portion, a plurality of spaced stiffening members arranged in said body portion and extending entirely across the body portion, each of the 35 said stiffening members having a pair of turned up ears at each end, a clamping plate arranged at each end of each of said stiffening members formed with turned down ears co-acting with the ears of said stiffening members, a pintle at each end of each of said stiffening members for connecting said clamping plate therewith, and a spring acting on each of said clamping plates and on each of said stiffening members for causing the clamping plate to tend to press against said stiffening members whereby the article placed in said holder will be held therein frictionally.

In testimony whereof I have signed my name to this specification in the presence of two subscribing witnesses.

THOMAS PAUL FORMAN.
